UNITED STATES PATENT OFFICE

JOHN SNEED, OF FERNDALE, MICHIGAN, ASSIGNOR TO THE MIDLAND STEEL PRODUCTS COMPANY, OF CLEVELAND, OHIO, A CORPORATION OF OHIO

ANTIRATTLER

Application filed October 1, 1928. Serial No. 309,664.

This invention relates to vehicle brake linkage and more particularly to a device for eliminating rattling of brake pull rods.

It is common practice that brake pull rods 5 extend alongside the side rails of the vehicle frame. Very often these rods are of considerable length and in the course of driving the vehicle with the brakes idle, may whip against the side rails causing a disagreeable 10 noise. Consequently, it is one of the objects of my invention to support the rods so that they will be held out of contact with the side rail or other parts of the chassis. Another object is to hold the rod without interfering 15 with its movement when the brakes are applied or released. A further object is to provide a simple and inexpensive mechanism capable of long life and hard usage.

Other objects will appear from the following 20 description of a preferred form of my invention, reference being had to the accompanying drawings. The essential characteristics are summarized in the claims.

In the drawings, Fig. 1 is an elevation of 25 a part of the side rail of the vehicle frame with the brake operating mechanism associated therewith; Fig. 2 is a top plan of the same side rail including an illustrative brake and brake linkage; Fig. 3 is an enlarged elevation of a portion of the side rail including 30 the anti-rattling device; Fig. 4 is a section taken along the lines 4—4 of Fig. 3; Fig. 5 is a section taken along the lines 5—5 of Fig. 3; and Fig. 6 is a plan view of the leaf spring 35 part used in my anti-rattling device.

Referring particularly to Figs. 1 and 2, I illustrate my invention in connection with the linkage used in a well known brake assembly wherein a side frame member or rail 40 40 supports a cross-shaft 2, usually operated by the foot pedal or similar means to actuate the brakes. Operatively connected to the shaft 2 is a brake pull rod 3 extending, in this instance, forwardly to actuate the front brake 45 4 of the vehicle. In this type of linkage the pull rod 3 is connected to a cable 5 which extends through a conduit 6 into the brake. Particularly in this type of construction, the pull rod 3 is pivotally supported at the cross-shaft and is supported by the flexible cable

5 at the forward end. As may be imagined, in idle position the pull rod may whip or may sway toward and away from the side rail causing rattling. To prevent rattling, I provide a device 10 which supports the pull rod 55 and resiliently urges it away from the frame and holds it a fixed distance therefrom. The parts are arranged as will presently appear so that the pull rod is perfectly free to move longitudinally of the device but is restrained 60 in its movement laterally thereof.

Referring particularly to Figs. 3 to 6 inclusive, I have illustrated the anti-rattling device in detail. Mounted on the web of the side rail is a U-shaped pressed metal part 11 65 with outturned flanges 12 through which rivets 13 or the like pass to secure the U-shaped part to the rail. The legs of the U-shaped part are spaced apart a distance slightly greater than the diameter of the 70 brake rod 3, see Fig. 4, and the base of the U is curved, as at 14, to substantially the same radius as the brake rod.

Referring particularly to Figs. 5 and 6, a leaf spring member 20 being cut down in its 75 middle portion, as at 21, to a width substantially equal to the diameter of the brake rod, is permanently disposed within the U-shaped part with the reduced portion 21 confined within the longitudinal limits of the 80 U-shaped part 11 so that longitudinal movement of the spring is limited by the shoulders 22 of the spring bearing against the edge of the legs of the U-shaped part, as at 23, see Fig. 3. Referring particularly to 85 Fig. 6, the leaf spring member is bowed upwardly in its mid portion and contacts with brake rod as at 25 and urges the brake rod into contact with the base of the U-shaped part. The ends of the spring member 20 90 may be upturned slightly as at 26 so that a smooth surface is presented to the web of the side rail, as at 27.

It will appear from the foregoing that as 95 the brake rod is drawn longitudinally of the U-shaped bracket, that there is no tendency to bind between the brake rod and the spring or between the spring and the side rail. Furthermore, the spring is not distorted by the normal operative movement of 100

the rod but the spring exerts a continuous pressure upon the rod and contacts with the base of the U-shaped bracket. It will further be appreciated that the arrangement of 5 parts is eminently simple and the device can be cheaply constructed and quickly applied; that the length of its useful life is indefinitely long and that the efficiency of its operation will continue throughout the life of 10 the vehicle. While I have illustrated and described a preferred form of my invention and its adaptation in a particular environment, I do not care to be limited in this or 15 any other manner other than by the claims appended hereto.

I claim:

1. An anti-rattling device for a vehicle 20 brake rod comprising a U-shaped bracket, secured to the frame of the vehicle, a leaf spring disposed at least in part within the bracket and acting between the frame of the vehicle and the rod and urging the rod into engagement with the base of the bracket away from the frame.

2. An anti-rattling device for a vehicle 25 brake rod, comprising a U-shaped bracket secured to the frame of the vehicle, a leaf spring extending generally parallel with the rod and disposed between the frame and the 30 rod at least in part within the bracket and urging the rod into engagement with the base of the bracket.

3. An anti-rattling device for a brake rod 35 constituting a U-shaped bracket secured to the side rail of a motor vehicle and encompassing the brake rod, a leaf spring extending generally parallel with the rod and held against movement longitudinally of the bracket and reacting between the side rail and 40 the rod to urge the rod into the part of the bracket most remote from the side rail.

4. An anti-rattling device for a brake rod 45 constituting a U-shaped bracket secured to the side rail of a motor vehicle and encompassing the brake rod, a spring held against movement longitudinally of the bracket and reacting between the side rail and the rod to urge the rod into the part of the bracket most remote from the side rail.

5. An anti-rattling device for a brake rod 50 lying adjacent the side rail of a motor vehicle comprising a leaf spring bowed upwardly in its mid portion and contacting with the brake rod at its mid portion and 55 contacting with the side rail of the vehicle at its ends, and means engaging the brake rod and limiting its movement away from the side rail against the pressure of said spring.

6. An anti-rattling device for a brake-rod 60 lying adjacent the side rail of a motor vehicle comprising a leaf spring bowed upwardly in its mid portion and contacting with the brake rod at its mid portion and contacting with the side rail of the vehicle at its 65

ends, and means encompassing the brake rod and at least part of said spring, and limiting movement of the rod away from the side rail against the pressure of said spring.

7. An anti-rattling device for a brake-rod 70 including a U-shaped bracket between the legs of which the rod extends and a leaf spring member having a reduced middle portion lying between the legs of the rod and forcing the rod toward the base of the U, 75 the end portions of the leaf spring being of greater width than the space between the legs of the bracket whereby the spring is restrained against movement longitudinally of the bracket. 80

8. An anti-rattling device for a brake rod, including a U-shaped bracket between the legs of which the rod extends and a leaf spring member having a reduced middle portion 85 lying between the legs of the rod and contacting with the rod, the end portions of the leaf spring being of greater width than the space between the legs of the bracket and having shoulders abutting the legs of the bracket, whereby the spring is restrained 90 against movement longitudinally of the bracket.

9. The combination of a vehicle frame, a 95 brake pull rod extending along the side thereof, and means for preventing rattling between the rod and the frame comprising a U-shaped bracket encompassing the rod and secured to the frame and a leaf spring bowed upwardly in its mid-portion and having its mid-portion disposed within the 100 bracket and contacting with the rod and having upturned end portions contacting with the frame, and presenting rounded surfaces for sliding engagement therewith. 105

10. The combination of a vehicle frame, a 110 brake pull rod extending along the side thereof, and means for preventing rattling between the rod and the frame comprising a U-shaped bracket encompassing the rod and secured to the frame and a leaf spring bowed upwardly in its mid-portion and having its mid-portion disposed within the bracket and contacting with the rod and forcing the rod to the base of the U-shaped part of the 115 bracket and having enlarged end portions of greater width than the opening through the bracket and contacting with the frame member and having its extreme ends upturned to present smooth surfaces to the frame member.

In testimony whereof, I hereunto affix my 120 signature.

JOHN SNEED.
